UNITED STATES PATENT OFFICE.

DE WITT C. HARRIS, OF FOND DU LAC, WISCONSIN, ASSIGNEE, BY MESNE ASSIGNMENTS, TO HARRIS TYPEWRITER MANUFACTURING COMPANY, OF FOND DU LAC, WISCONSIN, A CORPORATION OF WISCONSIN.

TYPE-WRITER.

1,115,068.

Specification of Letters Patent. Patented Oct. 27, 1914.

Original application filed April 15, 1912; Serial No. 690,756. Divided and this application filed March 20, 1913. Serial No. 755,582.

To all whom it may concern:

Be it known that I, DE WITT C. HARRIS, a citizen of the United States, residing at Fond du Lac, in the county of Fond du Lac 5 and State of Wisconsin, have invented certain new and useful Improvements in Type-Writers, of which the following is a specification.

This invention relates to typewriting machines and refers more particularly to an improved case shift mechanism therefor.

The invention pertains to a typewriting machine in which the impression platen and the printing instrumentalities are given a 15 relative case shift motion to bring the parts into different relations for printing the different types. This relative motion may be obtained by stationarily mounting the printing instrumentalities and moving the platen 20 with relation thereto, or by mounting the platen in a stationary manner and moving the said printing instrumentalities with relation to the platen. However, I prefer, and have illustrated in the attached drawings, 25 the construction in which the platen is stationary and the printing means movable.

Although my invention may be used in machines having various styles of printing devices, such as type wheel, segment or type 30 bar machines, the preferred construction is herein illustrated in which the printing devices consist of a plurality of independently pivoted type bars mounted upon a common support. Each of these type bars is provided with three types which are brought 35 into printing position at different times by the movement of the said type bar support.

I have herein shown my invention as applied to a typewriter of the so-called visible 40 and front-strike class, the type bar support being movable in a vertical direction, but obviously the invention is also applicable to other styles of machines.

This application is a division of my prior 45 application, Serial No. 690,756, filed April 15, 1912.

In the accompanying drawings, Figure 1 is a vertical front to rear section through a typewriting machine embodying the features 50 of my invention. Fig. 2 is a fragmental vertical sectional view taken on line 2-2 of Fig. 1, and illustrating the movable type bar segment. Fig. 3 is a vertical sectional view illustrating the guides for said type bar

segment. Fig. 4 is a horizontal sectional detail view of one of said guides. Figs. 5, 6 and 7 are views in a series illustrating the case shift mechanism in its three different operative positions. Fig. 8 is a fragmental vertical sectional view illustrating a portion of said mechanism. Figs. 9 and 10 are sectional detail views illustrating a portion of said mechanism in two different positions.

The machine to which I have herein shown my improvements as applied comprises a suitable framework consisting of a lower or base portion 10 and an upper or deck portion 11.

Since the present invention does not relate to the general mechanism of the machine, I will herein describe only such portions of said mechanism as assist in understanding this invention, reference being had to my former application above identified for a complete understanding of the machine.

The key lever mechanism for the type bars comprises a series of key levers 12, only one of which is shown, each of said levers being pivoted on a shaft 13 and connected by means of a link 14 with one arm of a bell crank lever 15, which lever is pivoted upon a shaft 16. The vertical arm of said bell crank lever is connected by a link 17 with a short arm 18 on the base of one of the type bars 19. The platen is indicated at 20.

The type bar segment 21, which is best shown in Fig. 2, is mounted in the frame of the machine for vertical movement. Said segment has three operative positions, of which the middle position is normal, and means, to be later described, is provided for shifting the segment in opposite directions from said normal position. The series of type bars 19 is pivoted on the arcuate portion of the segment. Said segment is mounted in a frame 22 which has in the present instance three arms 23 at its lower portion resting upon and suitably secured to lugs 24 and 25 extending inwardly from the base 10 of the machine. The frame 22 comprises two vertical side portions having grooved guide bars 26 mounted thereon. Preferably, these guide bars are mounted on the ends of screws 27 (Fig. 4) extending through slots 28 in the side portions of the frame 22. Said guides are adjustable laterally by screws 29 threaded in the frame and overlying said guides, the latter screws being

locked by set screws 30. The type bar segment 21 has two sides 32 having grooves therein complementing the grooves in the guides 26 to form races in which anti-friction balls 33 are mounted. Herein I have shown two balls in each of these races, said balls being spaced apart by means of a spacer plate 34. Projecting laterally from each of the sides of the segment is a stud 35 having an anti-friction roller 36 mounted thereon, which stud and roller are adapted to be actuated upon by the shifting mechanism to be later described. Stops 37 are carried upon lugs 38 in the upper ends of the sides of the frame 22 to limit the upward shifting movement of the segment. Similar stops 39 are mounted beneath the sides 32 of the segment to determine its downward shifting movement, as will be later explained, said stops 39 being in the present instance mounted upon the lugs 25 on the main frame. Stops 40 (Figs. 5 to 7), which may also be mounted in said lugs 25, are adapted to be engaged by portions carried by the shifting mechanism to determine the normal position of the segment. All of these stops may be of any suitable form, such as screws seated in their supports and carrying at their ends buffer plates *a* of suitable material, such as fiber or the like. Coiled springs 41, secured to the sides 32 of the type bar segment and to the frame 22, counterbalance the weight of said segment to render the operation thereof easier.

As hereinbefore stated, each of the type bars 19 carries three characters. The mechanism is so arranged that the middle row of types on said bars is used in ordinary writing, the upper and lower (or inner and outer) rows comprising capital letters, figures, or any other desired characters according to the use to which the machine is to be put. In using the upper and lower rows of types on the type bar, the type bar segment is shifted in opposite directions, said segment normally occupying its middle position. The mechanism for shifting said segment comprises a pair of arms 44 fixed upon the ends of a horizontal rock shaft 45 which is mounted in the lower frame. In the rear ends of said arms is rotatably mounted a rock shaft 46 (Figs. 8 to 10) and upon each end of this latter shaft is fixed an arm 47 having a slotted cam 48 at its upper end in which the roller 36 carried by the movable type bar segment lies. Said arms 47 when in their normal position thus form rigid links connecting the outer end of the arms 44 with the type bar segments. The arms 44 are swung to raise said type bar segment by means of either one of two shift levers 49 (only one being here shown) located at opposite sides of the machine, each of said levers being pivoted near its rear end on one end of the rock shaft 45 and having an

inwardly extending finger 50 which underlies the adjacent arm 44. Since both of the arms 44 are fixed on the rock shaft 45, when the outer end of either of the levers 49 is depressed, the arms 44 will be swung upwardly 70 and the type bar segment will be raised, the upward movement thereof being limited by the stop 37. In the return of the segment after an upward shift thereof, a shoe 51 carried by each of the arms 44 will abut 75 against the stops 40 to determine the normal position of the segment. Each of the shift levers 49 is held in its normal position by a coiled spring 52 attached at its upper end to the rear end of the lever and at its lower 80 end to a suitable bracket 53. The type bar segment is lowered, by swinging the cam arms 47 forwardly, which will cause the slotted cams 48 carried by the upper ends of said arms to draw the rollers on the segment 85 downwardly. Said arms are swung by similar means at opposite sides of the machine, each means comprising a bell crank lever 55, the arm 55^a of which lies alongside the arm 47 and has a finger 56 extending into a slot 57 in the arm 47. A flange 58 on said finger lies at the side of said arm opposite to said bell crank lever. The bell crank lever 55 is pivoted on a lug 59 on the base 10 of the machine, the pivot 60 being in register 90 with the rock shaft 46 when the latter is in its lower or normal position. A shift lever 61 pivoted between its ends upon the rock shaft 45 is arranged to engage at its rear end a roller 62 carried by the arm 55^b of the 100 bell crank lever 55 for rocking said lever. A spring 63 attached to the arm 55^b and anchored to the base of the machine normally holds the bell crank 55 and the arm 47 in position to maintain the type bar segment in its normal position. The shift lever 61 is held in its normal position by a coiled spring 64 attached to said lever and to the bracket 53. Both of the arms 47 being fixed on the rock shaft 46, when either of the 110 shift levers 61 at opposite sides of the machine is depressed, both arms 47 will be swung to lower the type bar segment until it abuts against the stops 39.

When the type bar segment has been 115 raised through the medium of the shift lever 49, an upright lug 65 on the rear end of the arm 44 is carried in front of the finger 56 upon the bell crank 55. Therefore, it will be impossible to swing said bell crank by depressing the segment-lowering lever 61. Likewise, when said segment-lowering lever has been depressed the segment-raising lever 49 cannot be depressed to raise the segment because the finger 56 on the bell crank has 125 been moved above the lug 65 on the arm 44. Thus only one of the segment-moving means can be operated at a time. The lug 65 also assists in preventing upward bouncing of the segment when shifted downwardly to 130

its lowermost position by reason of the overlying relation of the fingers 56 to said lug 65. Said lug also prevents upward movement of the segment through momentum when the latter is returning from its lowermost to its middle or normal position, because the finger 56 continues to overlie the lug 65 until the end of movement of the segment. The cams 48 by reason of their shape also assist in preventing movement of the segment through momentum or from bouncing.

While I have herein shown that embodiment of any invention which is preferred, I would have it understood that I do not limit myself to the exact structure disclosed, but aim to cover in the appended claims all modifications which fall within the scope of the invention.

20 I claim as my invention:

1. In a typewriting machine, the combination with a platen and printing instrumentalities, of case shift mechanism for effecting a relative shifting movement between said platen and said printing instrumentalities to any one of three positions, said case shift mechanism including a movable device operating to shift the movable element to one position, and means connecting said device to said movable element, said means being movable with the movable element to the mentioned shift position and being operable with relation to said movable element for shifting the latter to another position.

2. In a typewriting machine, the combination with platen and printing instrumentalities, of case shift mechanism for effecting a relative shifting movement between said platen and said printing instrumentalities to any one of three positions, said case shift mechanism including two shift keys, and means operatively connecting one of said keys to the movable element for shifting the latter to one position, said means including a device arranged to shift with the movable element to the mentioned shift position and being operable by the other key with relation to the movable element for shifting said movable element to another position.

3. In a typewriting machine, the combination of printing instrumentalities and a platen, one of which is shiftable relatively to the other to any one of three positions, means for shifting said shiftable element including a pivoted arm, and a cam member forming a connection between said arm and said shiftable element, said cam member being bodily shiftable with said arm in one shifting movement and being movable with relation to said arm in another shifting movement.

4. In a typewriting machine, the combination of printing instrumentalities and a

platen, one of which elements is shiftable relatively to the other to any one of three positions, of means for shifting said shiftable element including a pivoted arm, and a connection between said shiftable element 70 and said arm at a point spaced from the pivot of the latter, whereby swinging of said arm will bodily reciprocate said connection and shift said shiftable element to one position, said connection including a 75 cam arranged to be operated to shift said shiftable element to another position.

5. In a typewriting machine, the combination with a platen and printing instrumentalities, one of which elements is shiftable with relation to the other to any one of three positions, of a cam member operatively associated with the shiftable element, means for bodily moving said cam member to place said shiftable element in one of its shift 80 positions, and means for rocking said cam member to place said shiftable element in another of its shift positions.

6. In a typewriting machine, the combination with a platen and printing instrumentalities, one of which elements is shiftable with relation to the other to any one of three positions, the shiftable element carrying a projection, of a cam mounted for traveling movement and for rocking movement 95 and having a cam slot in which said projection lies, means for causing said cam to travel to carry the shiftable element to one position, and means for rocking said cam to change the position of said projection in 100 said cam slot and thereby move said shiftable element to another shift position.

7. In a typewriting machine, the combination of a platen and printing instrumentalities, one of which elements is shiftable relatively to the other to any one of three positions, of means for shifting the shiftable element including a movable device, and means forming an operative connection between said device and said shiftable element 105 and arranged to be bodily reciprocated by said movable device for moving the shiftable element in one direction from its normal position, said means including a cam operable to move said shiftable element in 110 the opposite direction from its normal position.

8. In a typewriter, in combination, a vertically slidable type bar segment, and means for shifting said segment comprising a pivoted arm, a connection between said arm and said segment, a shift lever pivoted between its ends, one end of said shift lever having a key thereon and the other end having a portion to underlie and engage said arm, and 115 swing the latter upwardly to shift said type bar segment.

9. In a typewriter, the combination of a framework, a type-bar support mounted therein for vertical movement and having a 120

4
pair of outwardly projecting studs, a pair of cam members positioned at opposite sides of said type-bar support, and having cam slots therein in which said studs lie, said cam members being mounted for traveling movement and for rocking movement, means for bodily moving said cams to shift said type-bar support to one position, and means for rocking said cams to shift said support to another position.

10. In a typewriter, in combination, a movable type-bar support, a pivoted arm, a cam member connecting the free end of said arm with said type-bar support, and means for swinging said arm and for operating said cam member with relation to said arm.

11. In a typewriter in combination, a movable type bar support, a pivoted element for moving said support in one direction, and a link operatively connecting said element with said support, said link having means which is operable to move said support in the opposite direction.

12. In a typewriter, in combination, a movable type bar support, a shift lever, and means connecting said shift lever to said support and being bodily reciprocable for moving the latter in one direction, said means including a pivoted cam operable to move said support in the opposite direction.

13. In a typewriter in combination, a movable type bar support, a pivoted arm, an arm pivoted upon the free end of the first mentioned arm, the second mentioned arm having a cam, a stud on said type bar support co-operating with said cam, means for swinging the first mentioned arm to move said type bar support in one direction through the medium of the second mentioned arm, and means for swinging the second mentioned arm to operate said cam and move said support in the opposite direction.

14. In a typewriter in combination, a movable type bar support, a pivoted arm, an arm pivoted on the free end of the first mentioned arm, a stud on said type bar support engaging the second mentioned arm, the latter normally forming a rigid link connecting the first mentioned arm with the type bar support, a shift lever arranged to swing the first mentioned arm to move said type bar support in one direction through the medium of the second mentioned arm, a cam on said second mentioned arm arranged to act upon said stud for moving said type bar support in the opposite direction, and a second shift lever arranged to swing said second mentioned arm to operate said cam.

15. In a typewriter in combination, a vertically movable type bar support, a rock shaft, two arms fixed on the opposite ends of said shaft, an arm connecting the free end of each of the first mentioned arms with said type bar support, the second mentioned arm having means for moving said

support downwardly, a shift lever arranged to swing one of the first mentioned arms for raising said support, and a second shift lever arranged to swing one of the second mentioned arms to operate said support-lowering means.

16. In a typewriter in combination, a vertically movable type bar support, a pivoted arm, an arm pivoted to the free end of the first mentioned arm and having a slotted cam at its free end, a roller stud mounted on said support and lying in the slot in said cam, a shift lever arranged to swing the first mentioned arm, and a second shift lever arranged to swing the second mentioned arm.

17. In a typewriter in combination, a vertically movable type bar support; means for shifting said support upwardly comprising a pivoted arm and a link connecting said arm to said support; means including a lever arranged to swing said link for shifting said support downwardly; and interlocking means on said arm and said lever arranged to prevent bouncing of the type bar support or movement of said support through momentum.

18. In a typewriter, in combination, a vertically shiftable type-bar support, a horizontal rock shaft, a pair of arms fixed on said shaft, a pair of cam members pivoted at their lower ends to the free ends of said arms, and operatively associated at their upper ends with said type-bar support, and means for rocking said shaft and for swinging said cam members.

19. In a typewriter, in combination, a vertically shiftable type-bar support having outwardly projecting studs thereon, a horizontal rock shaft, a pair of arms fixed on opposite ends of said shaft, a pair of cam members pivoted at their lower ends to the free ends of said arms, the upper ends of said members having cam slots in which said projections lie, a shift-key arranged to rock said shaft, and a second shift-key arranged to rock said cam members.

20. In a typewriter, in combination, a frame, a type-bar support mounted therein for vertical movement and having three operative positions of which the middle is the normal position, stationary stops in said frame for determining the upper and lower limits of movement of said type-bar support, means for shifting said support including a key-operable part mounted for up and down movement, a device connecting said part to said support for communicating motion to the latter when said part is raised, stop means against which said part is arranged to abut in its downward movement to determine the normal position of said support, and key-operable means arranged to actuate said device to shift said type-bar support downwardly with relation to said part.

21. In a typewriter, the combination of a platen and printing means shiftable with relation to each other, a pair of shift key levers at opposite sides of the machine, 5 means mounted for movement by either of said key levers in the same direction as the shiftable element, means connecting the second mentioned means with the shiftable element for transmitting movement to the latter in one direction, and another pair of shift key levers for operating said connecting means independently of the second mentioned means whereby to move the shiftable element in the opposite direction with 10 relation to the second mentioned means.
22. In a typewriter, in combination, a frame, a type-bar support mounted therein for vertical movement and having three operative positions of which the middle is the 15 normal position, stops mounted in said frame for determining the limit of motion of said support in opposite directions, shifting means for raising said support from its normal to its uppermost position, stationary stop means mounted on the frame and engageable by a portion of said shifting means when returning from said uppermost position, the latter stop means determining the normal position of said type-bar support, and means for moving said support downwardly with relation to the mentioned portion of said shifting means to carry the type-bar support into its lowermost position.
23. In a typewriter, in combination, a frame, a type-bar support mounted therein for vertical movement and having three operative positions of which the middle is the normal position, shifting means including a 20 vertically movable part, and a cam member connecting said part to the type-bar support, a stop in the upper portion of the frame to determine the upward movement of said part and said cam member, a second stop determining the downward movement of said part into normal position, and a third stop to determine the downward movement of the type-bar support when said cam member is operated.
24. In a typewriter, in combination, a frame, a type support mounted therein for vertical movement and having a pair of outwardly projecting roller studs, a pair of keys, and means including a pair of members having cam slots in which said roller studs lie to form an operative connection between said keys and said type support for shifting the latter in opposite directions.
25. In a typewriter, in combination, a 30 vertically movable type support, two independently pivoted key levers, and means connecting one of said key levers with said type support for shifting said support in one direction from its normal position, said means including a device independently movable with respect to said support and the remainder of said means, said device being individually operable by the other key lever for shifting said support in the opposite direction from its normal position.
26. In a typewriting machine, the combination with a platen and printing instrumentalities, one of which elements is shiftable with relation to the other to any one of three position, of case-shift mechanism including a movable device, and means acting as a link connection between said device and said shiftable element in one shifting movement, and acting as cam means to actuate said shiftable element in another shifting movement.
27. In a typewriting machine, the combination with a platen and printing instrumentalities, one of which elements is shiftable with relation to the other to any one of three positions, of case-shift mechanism including a movable device and a member connecting said device to said shiftable element, said member acting as a link in the upward movement of said element, and being operable as a cam to move said element downwardly.
28. In a typewriter, in combination, a vertically shiftable type-bar support, a movable shifting device, and means connecting said device to said support and acting at times as a link connection and at other times as a support-shifting means.
29. In a typewriting machine, the combination with a platen and printing instrumentalities, one of which elements is shiftable with relation to the other to any one of three positions, of case-shifting mechanism including a movable shifting device and means connecting said device to the shiftable element, said means being arranged to communicate motion at times from said device to said element, and at other times acting as independent shifting means.
30. In a typewriter, in combination, a vertically shiftable type-bar support, a key-lever, and means connecting said key-lever to said support for shifting the latter, said means including a portion acting at times to transmit the shifting motion from the key-lever to said support, and acting at other times as independent shifting means for moving said support to another shift position.
